CLAIM

We claim the ornamental design for a metal transaction device, as shown and described.

DESCRIPTION

FIG. 1 depicts a perspective view of a back face of a first embodiment of a metal transaction device.

FIG. 2 depicts a back elevational view of FIG. 1.

FIG. 3 depicts a perspective view of a back face of a second embodiment of a metal transaction device; and,

FIG. 4 depicts a back elevational view of FIG. 3.

The broken lines in the drawings illustrate environmental structure on the article and form no part of the claimed design.
